UNITED STATES PATENT OFFICE.

E. H. BUCKLAND, OF SPRINGFIELD, MASSACHUSETTS.

IMPROVEMENT IN WATCH-CASE SPRINGS.

Specification forming part of Letters Patent No. 77,579, dated May 5, 1868.

To all whom it may concern:

Be it known that I, E. H. BUCKLAND, of Springfield, Hampden county, Commonwealth of Massachusetts, have invented a new, useful, and Improved Catch-Spring for Watches; and I do hereby declare that the following is a full and clear description thereof, reference being had to the accompanying drawings, and to the letters of reference marked thereon:

In the drawings, Figure 1 is a plan view of the case of a watch with a partial section, and Fig. 2 a sectional view of the same part crosswise.

This invention consists of a new construction of a spring for the purposes above mentioned, and is intended to entirely obviate certain difficulties attending the old formation of spring.

In the ordinary method of constructing the springs for the purpose of throwing open the case and latching it when shut down two distinct springs have been used. These are short pieces of spring metal inserted in the case underneath the edge, one end of each being fastened by means of a small screw put through the rim of the case and through the spring. This requires a hole to be made through each spring-piece and corresponding holes in the case. Now when by any accident either of these springs are broken, in order to put a new one in its place it must be manufactured of the proper length and the hole for the screw drilled at exactly the proper spot to correspond with the holes in the case. This is a troublesome operation and requires a considerable expenditure of time for its performance. In my invention I totally dispense with the fastening-screws and make both springs in one, as I will now describe.

In the drawings it is seen that the spring A reaches past a straight line, bisecting the

circumference of the groove a in the case at both ends, thus occupying over half of the circumference. At one end, next to the hinge of the watch, is the tongue b, which throws up the back plate when it is released from the catch. In this arrangement of spring I prefer to form the catch itself upon the stud and let the spring press against it. Thus the catch d is formed upon the stud E, and is pressed outward by the spring A against it at this point. The advantages of this last arrangement are that the stud, confined by the spring on one side and prevented by the head formed upon it in the catch from slipping through, does not require any pin to be put through it in order to hold it in place. The catch may, however, be made directly upon the spring at a point opposite the hinge, if so desired.

In putting in these springs all that is required to fasten them in place is to compress them sufficiently to allow them to get inside the groove, and upon releasing them they spring against the side of the watch-case inside, and being more than half the circumference in length they do not require any fastening to hold them in place.

Now having described my invention, what I claim as new, and desire to secure by Letters Patent, is—

1. The spring A, formed of one piece and reaching over half the circumference of the case and forming both catch and throw up at each end, respectively, substantially as and for the purpose shown.

2. The stud E, with the catch d formed upon it, substantially as and for the purpose shown.

E. H. BUCKLAND.
